GREASE GUN RACK

Oliver B. Elliott, 150 Hillsdale, Wichita, Kans.

Filed Dec. 12, 1961, Ser. No. 67,881

Term of patent 3½ years

(Cl. D80—9)

FIG. 1 is a front elevational view of a grease gun rack, showing my new design, wherein the upstanding center member is obliquely disposed and the horizontal arms are evenly spaced;

FIG. 2 is a rear elevational view thereof;

FIG. 3 is a side elevational view thereof;

FIG. 4 is a front elevational view of a modified form of the grease gun rack disclosed in FIG. 1, wherein the upstanding center member is vertically disposed and the four horizontal arms are spaced in pairs at the top and bottom thereof;

FIG. 5 is a rear elevational view of the form shown in FIG. 4; and

FIG. 6 is a side elevational view of the form shown in FIG. 4.

The design is characterized by a single generally rec-

tangular upstanding center member in combination with spaced horizontally disposed elongated rectangular shaped arms connected at their centers to the upstanding member. The top and bottom edges of the upstanding member are parallel with said arms and each of the horizontal arms are provided with spaced projecting hooks.

I claim:

The ornamental design for a grease gun rack, as shown and described.
